UNITED STATES PATENT OFFICE.

MARY E. THOMPSON, OF NEWARK, NEW JERSEY.

VENTILATING DEVICE.

1,114,938.

Specification of Letters Patent. Patented Oct. 27, 1914.

Application filed September 10, 1913. Serial No. 789,089.

To all whom it may concern:

Be it known that I, MARY E. THOMPSON, a citizen of the United States, residing at Newark, in the county of Essex and State 5 of New Jersey, have invented certain new and useful Improvements in Ventilating Devices; and I do hereby declare the following to be a full, clear, and exact description of the invention, such as will enable others skilled in the art to which it appertains to 10 make and use the same.

This invention relates to ventilating devices capable of a wide range of use, and has for its object to produce an apparatus 15 which would be simple and certain in operation, comparatively inexpensive to manufacture, and one that while permitting a free ventilation of the air will also exclude rain.

20 With these and other objects in view the invention consists in the novel details of construction and combinations of parts more fully hereinafter described and particularly pointed out in the claims.

25 Referring to the accompanying drawings forming a part of this specification in which like numerals designate like parts in all of the views, Figure 1 is a diagrammatic sectional view of a ventilator made in accordance with my invention; Fig. 2 is a sectional view taken at right angles to the plane on which Fig. 1 is taken; Fig. 3 is a diagrammatic sectional view of a modified form of my invention applied to a vault light opening or cellar; Fig. 4 is a detail diagrammatic view of a modified means of lifting my ventilator and Fig. 5 is an enlarged detail view showing a fusible connection in the operating chain.

40 1 indicates the frame of a sky light, vault or other inclosure it is desired to ventilate, and 2 a ledge or rim adapted to receive the packing 3 of the frame 4 of the sky light or other cover. This frame when used for a 45 sky light is provided with the glass members 5, of which there may be any desired number, and 6 represents intermediate supporting pieces for the said glass. In order to secure the glass in place I provide on the 50 frame 4, the holding members 7, which may be secured in place by the screws or other means 8, and I further provide the packing or other material 9 carried by said frame 4. The frame 4 is also provided with a groove 55 or trough 60 for collecting and draining off, by means of the drainage holes 61, any wa-

ter which may condense upon the under side of the glass members 5. In like manner each of the members 6 may be provided with glass holders 10 and packing material 60 11 as shown.

To a plurality of the supporting cross pieces 6 I secure the T-shaped hinge members 12 and secure thereto by the pins or bolts 13, the upper ends 14 of the lifting 65 rods 15, each sliding in the guides 16, and provided with the rack teeth 17 meshing with the teeth of an idler 18, meshing with a pinion 20, rigid with the lever 21, and controlled by the chain or cords 22. The said 70 chain connection 22 passes over the pulley 23 carried by a support in the inclosure to be ventilated, thence over a secured pulley 24, and may pass over still a third pulley 25 if desired, whence it leads to any desired 75 point not shown when it may be secured or manipulated at will, all as will be clear from Fig. 1.

It is obvious from the mechanism so far disclosed that if one pulls on the chain connection 22, the levers 21 will be moved toward the glass, the idlers 20 will be turned in opposite directions seen in Fig. 1, the pinions 18 will be turned also in opposite directions, the racks 17 will be moved upwardly, 85 and the whole frame 4 and glass panes 5, moved from their full line positions to positions indicated by the dotted lines in said Fig. 1. When the frame 4 is thus raised it is evident that there will be a free circulation of air through the opening thus produced, while rain will be excluded. 90

In the modified form of construction shown in Fig. 3, 35 represents a vault light, cellar door or other cover, 36 a frame work 95 in all respects the same or similar to the frame 4 or otherwise constructed, 37 a drain for dew water or other material which may find its way on to the frame 36, 38 a lever directly attached to the pinion 18 and 39 a 100 cord or chain connection leading from the lever 38 to the pulley 40. The other parts illustrated in said figure are, or may be the same as in Fig. 1. It will likewise be apparent that should one pull upon the chain 105 or cord connection 39 at the operating point not illustrated, the said levers 38 will be moved downwardly as seen in Fig. 3, and through the pinions 18 the racks 17 and lifting rods 15 the frame 31 will be moved from 110 its full line position to its dotted line position shown in said figure, whereupon the

openings in the cover 35 will be completely closed. But when the said frame 35 is in the full line position shown a free ventilation of air is had through the space 42, 5 while rain is excluded. During this motion the pipe 37 which has a telescoping connection with its guide 43 moves up with the frame 36, but is still adapted to deliver water into said guide 43 which may be 10 drained off by means of a pipe 44.

In both of the forms of my invention I prefer to provide a fusible link 45 or other automatic means for operating the ventilator to a closed position should a fire break 15 out. This said fusible link may be placed at any convenient point in the chain connection 22 or 39, and I have illustrated it for convenience only as being located near the pulleys 24 and 40. It is shown in detail 20 in Fig. 5 wherein the connection is illustrated as a chain, and its construction is as follows: One member of the chain is provided with a ring 46 and another member of said chain is provided with another ring 25 47 which is too large to pass through the ring 46. The two members of the chain are connected as illustrated, by the fusible link 45, and it results from this construction that when the link is melted under the operation 30 of a rise of temperature the two members of the chain 39 or 22 as the case may be, will slide over each other until the two rings 46 and 47 contact, whereupon the chain will not lengthen any further. In the meantime 35 should the frame work 4 illustrated in Fig. 1 be open as indicated in dotted lines and the fusible link 45 broken, it is evident that the parts will descend by gravity into their full line positions, whereupon the ventilator 40 will be closed. On the other hand should it be desired to counterbalance the frame work 4 I may add to the lifting rods 15 the weighted levers 50, which tend constantly to open the ventilator, but the weights 51 of 45 which are so adjusted as to not quite overpower the weight of the frame 4 and its associated parts. These weights 51 render the operation of my sky-light easy. In the same way should it be desired to counterbalance 50 the weight of the frame 36, a device precisely the same or similar as that illustrated in Fig. 4 may be associated with the lifting rods 15, so as to slightly overpower the weight of the frame work 36 and to constantly bring the said frame 36 into its dotted line position. In such case the fusing of 55

the link 45 would effect the automatic closure of the said frame 36.

It is understood that the foregoing illustrations and disclosures are merely examples 60 of two embodiments of my invention, and that I am not to be restricted to the said disclosure except as may be required by the claims, for it is obvious that those skilled in the art may vary the details of construction 65 as well as the arrangement of parts without departing from the spirit of my invention:

What I claim is:—

1. In a ventilating apparatus the combination of a cover; a seat for said cover; a plurality of supporting racks for said cover; a pinion engaging each rack; a second pinion engaging each first named pinion; a lever associated with each second pinion for 75 moving said racks and cover up and down; and means comprising a flexible connection for controlling said levers, racks and pinions at a single point, substantially as described. 80

2. In a ventilating apparatus, the combination of a transparent cover; a seat for said cover; a plurality of racks for supporting said cover; a pinion for engaging each rack; a lever provided with a second pinion 85 for engaging each first named pinion; a flexible connection associated with each lever; pulleys for guiding said flexible connection and guides for said racks causing the same to move said cover in a vertical 90 direction, whereby a free circulation of air may be had, substantially as described.

3. In a ventilating apparatus the combination of a combined ventilator and skylight comprising a transparent cover; a seat 95 for said cover; a plurality of racks for supporting said cover; a pinion for engaging each rack; a lever carrying a second pinion for engaging each rack engaging pinion; a flexible connection associated with each lever 100 provided with two members slidable with relation to each other and adapted to receive a fusible member; and pulleys for guiding said flexible connection, substantially as described. 105

In testimony whereof I affix my signature, in presence of two witnesses.

MARY E. THOMPSON.
